US00D990498S

(12) **United States Design Patent** (10) Patent No.: **US D990,498 S**
Wang et al. (45) Date of Patent: **** Jun. 27, 2023**

(54) **DISPLAY SCREEN OR PORTION THEREOF WITH A GRAPHICAL USER INTERFACE**

(71) Applicant: **Beijing Zitiao Network Technology Co., Ltd.**, Beijing (CN)

(72) Inventors: **Juan Wang**, Beijing (CN); **Shijia Hu**, Beijing (CN)

(73) Assignee: **BEIJING ZITIAO NETWORK TECHNOLOGY CO., LTD.**, Beijing (CN)

(**) Term: **15 Years**

(21) Appl. No.: **29/805,040**

(22) Filed: **Aug. 24, 2021**

(30) **Foreign Application Priority Data**

(57) **CLAIM**

We claim the ornamental design for a display screen or portion thereof with a graphical user interface, as shown and described.

DESCRIPTION

The FIGURE is a front view of a display screen or portion thereof with a graphical user interface showing the new design.

The outermost broken line rectangle illustrates a display screen or portion thereof and forms no part of the claimed design. The remaining broken lines illustrate portions of the graphical user interface that form no part of the claimed design.

1 Claim, 1 Drawing Sheet
